Primary Examiner — Catherine Ho(74) *Attorney, Agent, or Firm* — J. Scott Young**(57) CLAIM**

The ornamental design for a label set for an inhalation device, as shown and described.

DESCRIPTION

FIG. 1 is a perspective view of the first embodiment of a label set for an inhalation device shown in an environment of use;

FIG. 2 is a front view thereof;

FIG. 3 is a back view thereof;

FIG. 4 is a perspective view of the second embodiment of a label set for an inhalation device shown in an environment of use;

FIG. 5 is a front view thereof; and,

FIG. 6 is a back view thereof.

The broken lines in the above drawings depict environmental subject matter only and form no part of the claimed design.

1 Claim, 6 Drawing Sheets**Related U.S. Application Data**

15, 2015, now Pat. No. Des. 768,241, which is a continuation of application No. 29/469,595, filed on Oct. 11, 2013, now abandoned.
